UNITED STATES PATENT OFFICE.

DAVID M. POLLACK, OF CHICAGO, ILLINOIS.

DESIGN FOR A CLOCK-CASE.

SPECIFICATION forming part of Design No. 24,273, dated May 7, 1895.

Application filed March 21, 1895, Serial No. 542,712. Term of patent 3½ years.

To all whom it may concern:

Be it known that I, DAVID M. POLLACK, a citizen of the United States, residing at Chicago, in the county of Cook and State of Illinois, have invented and produced a new and original Design for Clock Cases or Frames, of which the following is a specification, reference being had to the accompanying drawings, forming a part thereof.

10 In the accompanying drawings, Figure 1 is a front elevation showing my design; and Fig. 2, a transverse section taken on line 2 of Fig. 1, looking in the direction of the arrow, these two views being deemed necessary to 15 fully illustrate my design.

The leading feature of my design consists in a raised figured surface, the outlines of which, when viewed in elevation—as shown in Fig. 1—will fall entirely within the circular outline or circumference of the frame.

20 A is the raised, central portion of the frame, which is circular in its general contour; and B is the rim of the frame, which is also circular in its general contour. These parts are 25 also circular in their inner contour, and the central portion is provided with a central opening to receive a clock, similar to that shown in the drawings.

In transverse section, the outline of the parts presented—as in Fig. 2—is irregular, the 30 parts B and C forming raised bosses or steps, the part C being circular when viewed in outline of elevation, and of substantially the same size as the portion A. The central portion is provided with indentations, a, to form 35 an irregular surface, as shown in Fig. 2, and to this central portion are secured leaves, D, D. The outer rim, B, is provided with raised configurations, b, forming a kind of lace work with rosettes in the center, and an outer figured edge, b', of a peculiar configuration similar to that shown in Fig. 1 of the drawings—the whole presenting to the eye the combined effect of the smooth circular outline with ornamental, raised figured surfaces within. 45

I claim—

The design for a clock case or frame herein shown and described, the same comprising a raised circular inner portion, A, having indentations, a, bordered by a circular rim B, 50 provided with raised ornamental figures, b b', substantially as herein described.

DAVID M. POLLACK.
